E. J. G. PHILLIPS.
MEANS FOR SECURING OVERHEAD TRACKS IN PLACE.
APPLICATION FILED NOV. 10, 1921.

1,422,473.

Patented July 11, 1922.

UNITED STATES PATENT OFFICE.

ELLIS J. G. PHILLIPS, OF AURORA, ILLINOIS, ASSIGNOR TO RICHARDS-WILCOX MANUFACTURING COMPANY, OF AURORA, ILLINOIS, A CORPORATION OF ILLINOIS.

MEANS FOR SECURING OVERHEAD TRACKS IN PLACE.

1,422,473.

Specification of Letters Patent. Patented July 11, 1922.

Application filed November 10, 1921. Serial No. 514,251.

To all whom it may concern:

Be it known that I, ELLIS J. G. PHILLIPS, a citizen of the United States, and a resident of Aurora, in the county of Kane and State 5 of Illinois, have invented certain new and useful Improvements in Means for Securing Overhead Tracks in Place, of which the following is a specification, reference being had to the accompanying drawings.

10 This invention relates to improved means for securely holding in position the overhead track upon which run the usual wheeled carriages that have depending from them suitable devices for engaging and sustaining 15 doors or other objects. It is important in structures of this character that the track be held very rigidly so that it will not as a whole be apt to shift even slightly from the position in which it has been originally 20 placed, and it is equally important that the several sections of which such a track is usually formed shall remain in perfect alinement in order that the wheeled carriages that run thereon shall operate with the least 25 amount of friction and without obstruction or jar at the joints of the track. It is the object of this invention to provide, in connection with the devices that are employed to suspend the track, cheap and simple 30 means that will force the track into such frictional engagement with the brackets that the track rests upon that all liability of any movement of the track as a whole relative to such brackets will be obviated, and, where 35 the abutting end portions of two sections of such track are supported by a single bracket, as is usually the case, such end portions will by their frictional engagement with that bracket be held in the required perfect alinement.

Briefly stated, I attain said object by arranging over the bracket and at some little distance therefrom a pressure member, which is here shown as a flat metal plate, having 45 downwardly-turned end portions that rest against the top wall of the track, and providing means for forcing said pressure member down to cause its said turned end portions to bear on the top of the track and thus 50 frictionally hold the track between such end portions and the lower inturned part of the bracket, said forcing means preferably taking the form of a nut on the screw-threaded rod that depends from a suitable arm and 55 supports the said bracket. That which I be-

lieve to be new will be set forth in the claims.

In the drawings:

Fig. 1 is a perspective view of a portion of a trolley track held in suspended position by a screw-threaded rod depending from an arm and carrying at its lower end one of the brackets in which the track is located, and showing in connection therewith my improvements for clamping the track and bracket together.

Fig. 2 is a plan view of the parts shown in Fig. 1.

Fig. 3 is a vertical section taken substantially on line 3—3 of Fig. 2; and

Fig. 4 is a cross-section taken on line 4—4 of Fig. 3.

Referring to the several figures of the drawings,—A indicates an arm which, in the construction here shown, is formed from a single piece of comparatively wide sheet metal bent upon itself to form two parallel members which at their end portions are respectively turned outward at a right angle to form attaching ears a adapted to lie against a wall or other support and be secured thereto by bolts b. Each of the parallel spaced-apart members of the arm A is shown as provided near its inner end with an integral boss c which bosses abut and act 75 to hold the two members in proper spaced-apart relation. Each of said members is also shown as provided with an integral rib d, which ribs act to stiffen the arm as a whole, as will be understood.

Located between the spaced-apart members of the arm A is a screw-threaded rod 5 which is held at any desired point with respect to said arm by means of nuts 6 and 7, which respectively bear against washers 8 and 9 that lie opposite the upper and lower edges respectively of the spaced-apart members of the arm A. As will be understood, by having those nuts loosened the rod can be shifted to any desired point and then secured firmly in place by tightening the nuts against their respective washers, so as to force such washers tightly into frictional engagement with the edges of the arm.

No claim is here made for the construction 105 of arm shown, or for such arm in combination with the rod 5 and a clamping means for securing it to the arm, as such subject matter will form the basis for a separate application.

10 indicates a section of trolley track of well known form, which is made from a single piece of sheet metal bent upon itself to form a top wall and two parallel side walls, the latter having their lower marginal portions inturned to form parallel rails upon which run the wheels of any ordinary load-supporting carriages, the usual pendants from such carriages extending through the 10 central slot of the track between the said rails, as usual. At intervals the track will be provided with supporting brackets 11 which, as usual, conform approximately to the shape of the track, and so conforming to 15 such shape will of course have inwardly turned marginal portions at its lower end upon which the rail portions of the track 10 rest. As usual, these brackets, while conforming generally to the shape of the track 20 10, will be somewhat higher than such track, in order to accommodate between the inner face of the top wall of the bracket and the outer face of the top wall of the track a head or enlargement of the member that 25 supports the bracket from the arm A or its equivalent. In this instance, of course, the screw-threaded rod 5 is such supporting member, and it passes freely through an unthreaded hole in the top wall of the bracket, 30 and its head, above referred to, is indicated by 12. The bracket is prevented from any turning movement relative to the rod 5 and its head by any suitable means, such means in the construction shown being a small rib 35 13 struck down from the top wall of the bracket adapted to lie in contact with the head 12.

While the brackets such as 11 will ordinarily fit snugly against the sides of the 40 track, and will therefore hold the track as a whole in approximately proper position, it is found that such fit of the parts cannot be relied upon to maintain the several sections of the track in that perfect alinement that is 45 requisite for a perfectly smooth movement of the wheeled carriages that operate in the track. To secure and maintain a more nearly exact fit of the sections of track one with the other, and for holding the track as a 50 whole in the desired position, I have provided means for so bearing down upon the track as to force its inturned rail members into close frictional engagement with the underlying and correspondingly inturned members 55 of the brackets, such means being preferably duplicated in connection with each of the brackets. The means for thus applying the desired pressure to the track comprises, in the construction shown, a plate 14 provided centrally with a hole 15, through 60 which loosely passes the screw-threaded rod 5. This plate had downwardly-turned end portions 16, which at their edges rest upon the top wall of the track 10 adjacent to the 65 opposite sides of the bracket, such turned

portions 16 being of sufficient length to hold the main or body portion of the plate at a slight distance above the track 10, as clearly shown in Fig. 3. Upon the screw-threaded rod 5 is a nut 17, which is adapted to be 70 screwed down firmly against the plate or pressure member 14, and when so screwed down will, of course, cause the turned ends 16 of the plate to bear forcibly against the track, which in turn, as will be understood, will force the track itself into tight frictional engagement with the inturned parts of the bracket that lie beneath the track rails. The degree of pressure can of course be regulated as desired by the extent 75 to which the nut 17 is turned.

While my improvements are of value in connection with supporting brackets such as 11 that may be located intermediately the ends of a track section, yet such improvements will be found of especial value in connection with a bracket that receives the abutting ends of two track sections, as shown in Fig. 3, for when so used the down-turned end portions of a pressure device will respectively bear upon the two track sections at points approximately the same distance from the joint between them, and the pressure will be equally applied to those two sections, with the result that they will be 90 forced into and held in as near perfect alinement as is possible to attain, and thus eliminate almost wholly the disadvantages arising from a joint in the track.

What I claim as my invention, and desire 100 to secure by Letters Patent is,—

1. The combination with an overhead track and means for supporting it in place, said means comprising a bracket extending over and partially beneath the track, of a 105 pressure member overlying the upper wall of said bracket and resting upon the track, and means for forcing said member firmly down against said track.

2. The combination with an overhead 110 track and means for supporting it in place, said means comprising a bracket partially embracing the track, of a plate overlying the upper wall of said bracket, said plate having turned end portions that rest upon the 115 track and of a length to normally hold the plate away from the track, and means for forcing said turned end portions firmly against the track.

3. In a device of the class described, the 120 combination with a vertical screw-threaded supporting rod, a track, a bracket connected with the lower end of said rod and partially embracing said track, of a plate extending across said bracket and having downwardly-turned end portions that rest upon the top 125 of said track and hold the plate at a distance from the bracket, and a nut upon said rod adapted to be turned to bear against the plate.

4. In a device of the class described, the combination with an arm, a vertical screw-threaded rod depending therefrom and having a head on its lower end, a bent bracket, 5 through an opening in the upper wall of which said rod extends, a track in said bracket below the head on said rod, a plate over said bracket, through an opening in which plate said rod also passes, said plate 10 having downwardly-turned end portions that rest upon the track at opposite sides of the bracket and are of a length to normally hold the plate out of contact with the bracket, and a nut on the screw-threaded rod adapted to be turned down against said plate.
5. The combination with an overhead
- hollow track slotted in its under surface, of a bracket shaped substantially like the track but of greater height than the track, a pressure member overlying the upper wall of the 20 bracket and bearing upon the track, a supporting device that extends through both the pressure member and the bracket and has an enlargement on its lower end that is located in the space between the upper portions of the track and bracket, and means for forcing said pressure member firmly against said track to cause the lower portions of the track and bracket to be held in close engagement. 25
